United States Patent Office.

ROBERT HUTTON, OF WILLIAMSBURG, NEW YORK, ASSIGNOR TO HIMSELF
AND WILLIAM MEE, OF SAME PLACE.

Letters Patent No. 60,736, dated January 1, 1867.

IMPROVEMENT IN BLINDS.

The Schedule referred to in these Letters Patent and making part of the same.

TO ALL WHOM IT MAY CONCERN:

Be it known that I, ROBERT HUTTON, of Williamsburg, in the county of Kings, and State of New York, have invented new and useful improvements in "Window Blinds;" and I do hereby declare that the following is a full, clear, and exact description thereof, which will enable others skilled in the art to make and use the same.

The present invention relates to that class of window-blinds in which the slats composing the same are hung so as to swing or turn in the side pieces of the blind frame; and it consists principally in a novel manner of connecting the several slats to the operating rod employed for removing the slats, which rod, in lieu of being arranged along the centre line of the slats, is at one end of each of the same, and is there hung directly to the ends of the slats by suitable tenons or pins formed thereon, so that when the slats are closed the said rod will offer no obstruction to the raising and lowering of the sashes of the window-frame in connection with which such blind is used.

This invention also consists in a novel manner of hanging one end of the slats between the upper and lower one of each series of slats of the blind-rods; and also in the use of a spring or springs, in connection with one or more of the tenons of the blind-slats, for the purpose of so binding them as to prevent their turning too freely and thus becoming disarranged when once brought to any desired position, whether more or less opened or closed.

In the accompanying plate of drawings my improvements are illustrated—

Figure 1 being a front view of a blind constructed according thereto, with a portion of one of the side pieces of such frame broken out or away to show the arrangement of the spring in connection with the tenon of one of the blind-slats; and

Figure 2, a transverse vertical section taken in the plane of the line xx , fig. 1.

Similar letters of reference indicate like parts.

A, in the drawings, represents a blind-frame, and B its several slats, that at one end are all hung by tenons, C, in and to one of the side pieces D of the blind-frame, but at their others, with the exception of the upper and lower one of the series, (which are hung by tenons to the opposite side piece F of the blind-frame,) are hung by pins or tenons G, formed at such end to vertical rods H, one upon the outside and the other upon the inside of the blind; these rods being also similarly hung to the upper and lower ones of the series of slats, thus sustaining the slats in their proper relative position, as is obvious without any further explanation.

By the rods H the slats are operated, and as they are upon the ends of the slats in lieu of along their centre line, or midway between their two ends, such rod of the two rods as is upon the inside of the blind when it is closed upon the window, is, if the slats are closed one upon another by properly operating such rod, in such a position as to be out of the way, or in other words out of the line of movement of the sashes of the window when raised or lowered for being opened or closed, as the case may be—an advantage of much importance.

In connection with the tenons of the slats, a spiral spring, L, is arranged in the side of the blind-frame in which such tenon turns, so as to bear upon the end of the said tenon, as plainly shown in fig. 1, and thus to bind or hold the same sufficiently tight to prevent its turning freely or easy, and thus to become disarranged, as it were, in position, after the slats have been once set, either more or less opened or closed, as may be found desirable.

I claim as new, and desire to secure by Letters Patent—

A blind having its rod for operating the slats of the same hung to one end of such slats, substantially as and for the purpose described.

The above specification of my invention signed by me this 19th day of September, 1866.

ROBT. HUTTON.
